DESIGN FOR AN INFANT'S PLAY PAD

Frank T. J. Roemer, Fort Wayne, Ind.

Application February 7, 1936, Serial No. 61,029

Term of patent 14 years

To all whom it may concern:

Be it known that I, Frank T. J. Roemer, a citizen of the United States, residing at Fort Wayne, in the county of Allen and State of Indiana, have invented a new, original, and ornamental Design for Infants' Play Pads, of which the following is a specification, reference being had to the accompanying drawing, forming part thereof.

Figure 1 is a plan view and Fig. 2 an elevation

of an infant's play pad showing my new design. The sheet having the decorated border thereon is relatively thin and the central pad attached thereto is relatively thick.

I claim:

The ornamental design for an infant's play pad, as shown and substantially as described.

FRANK T. J. ROEMER.
